UNITED STATES PATENT OFFICE.

ARTHUR C. McWILLIAMS, OF SOUTH BEND, INDIANA.

LAMP-SOCKET.

1,167,579.

Specification of Letters Patent. Patented Jan. 11, 1916.

Application filed January 12, 1914. Serial No. 811,663.

To all whom it may concern:

Be it known that I, ARTHUR C. McWILLIAMS, a citizen of the United States, residing at South Bend, in the county of St. Joseph and State of Indiana, have invented a certain new and useful Improvement in Lamp-Sockets, of which the following is a specification.

My invention relates to lamp sockets, especially of the type used for street lighting.

In lighting streets or other outdoor places by incandescent lamps it is usual to connect a number of lamps in series and in such case it is necessary to provide means whereby, when a filament of any one of the lamps is burned out or broken and the circuit thus interrupted, the circuit will be automatically reestablished by devices located in the lamp socket and capable of shunting the lamp circuit when it breaks. The shunting or short circuiting of broken lamp filaments has been accomplished by so called "film sockets" in which two terminals, normally insulated by an interposed film of insulating material, are arranged in multiple with the principal terminals of the socket, so that the instant increase of voltage (which results from full line voltage being impressed upon the occurrence of the break) burns out or punctures the film and closes the circuit through the two adjacent terminals thus providing a new path for the current. A short circuiting spring contact is also provided and so arranged in the socket as to afford a path for the current when the lamp is absent. But the film sockets heretofore employed have had disadvantageous characteristics which it is my purpose to eliminate.

With this general object in view it is my purpose to provide a film socket which, practically speaking, cannot be misoperated; also to provide a socket which is simple, safe against short circuits and leakage currents, weather proof, durable, attractive in appearance and cheap to manufacture.

More specifically my objects are first, to provide convenient means for replacing burned out films, second to render this possible without danger of having them damaged in the process, third to provide means for securely holding the film and preventing it from "creeping" as a result of the stresses exerted upon the parts by the action of the wind, fourth to provide a construction such that there shall be no exposed live metal parts on the back of the socket, fifth to pro-

vide a construction in which the parts are so securely held together that the action of the wind cannot work any of the parts loose and permit the lamp to drop.

In one type of known socket it is necessary to always have the lamp in the socket when receiving the part containing the filament, otherwise the film will become punctured.

One of my objects is to provide a construction such that the lamp alone may be removed or the film holder and the lamp together may be removed without opening the line or puncturing the film.

Another object is to provide means for compressing the film in such manner that it will always operate at practically the same puncture voltage.

It is also an object to provide a construction adapted to utilize circular or ring type filaments which on account of the exposed area give a liberal puncture surface.

It is also an object to provide a removable film holder such that the operating electrician may, if pressed for time or operating under adverse weather conditions, supply himself with a number of film holders containing fresh films. Then when he comes to a broken lamp he may simply remove the old film holder and substitute a new one containing a fresh film; replacing the burned out film in the old holder at his leisure after returning to the central station.

These several characteristics are not all individually new, but some of them are new in themselves, and furthermore, so far as I am aware, my device is the first to combine them all in a single structure.

I accomplish my objects by the mechanism illustrated in the accompanying drawings in which—

Figure 1 is an axial section on the line 1—1, Fig. 3. Fig. 2 is similar to Fig. 1 but shows the film holder and lamp removed from the base. Fig. 3 is a view of the base looking directly thereinto. Fig. 4 is a sectional view on the line 4—4, Fig. 3. Fig. 5 is a rear view of the base. Fig. 6 is a face view of the parts in which the film is contained. Fig. 7 is a vertical section on the irregular line 7—7, Fig. 8. This line of section is selected to more clearly illustrate the relation of the binding posts and other parts of the base. Fig. 8 is a bottom view of the stationary parts of Fig. 7. Fig. 9 is a perspective on an increased scale of the metal-

lic ring which holds the film between itself and the inner film holding shell. Fig. 10 is a perspective of the upper end of the internal shell with the insulating ring in position. Figs. 11 and 12 are face and edge views respectively of the dielectric, destructible films. Fig. 13 is a central section of the shoe against which the film holder abuts.

Similar numerals refer to similar parts throughout the several views.

The base 1 is formed of porcelain or other insulating material and is designed to be attached to a suitable stationary support. Within this base is located a metallic shell 2 which has screw threads formed therein and is permanently connected to one of the binding terminals. In the present design the connection is by means of a screw 3 connected to a strip 4 connected to a terminal post 5 having a binding screw 6. The parts, 3, 4, 5 and 6 are embedded in the base, the strip 4 being overlaid by insulating compound 7 as best shown in Fig. 4. An extra screw 8 is desirable for assisting the screw 3 to hold the shell 2 securely in position. This screw is held at the back of the base by a nut 9 overlaid by insulating compound 10. The opposite binding terminal consists of the parts 11, 12 and 13 similar in construction and function to the part 4, 5 and 6 respectively. The strip 11 is overlaid by insulating compound 11^a as best shown in Figs. 1 and 2 and is electrically connected to the spring contact 13^a and shoe 14 by a screw 15. The part 13^a constitutes a short circuiting switch and normally tends to engage the inner end of shell 2 as shown in Fig. 2. Said switch is operated by a post 16 which is centrally located and formed of conductive material. Shoe 14 is also of metal and has a flange 14^a (see Fig. 13) which is annular and makes electrical contact with the film holder when the latter is screwed home into the shell 2. It also acts as a stop to limit the distance to which the film holder may be inserted.

The film holder comprises the metallic shell 17, the annular metallic plate 18 and the insulating ring 19. Shell 17 has external and internal threads, the external threads enabling it to screw into the shell 2 and the internal threads enabling it to receive the base 20 of the lamp. Said shell 17 is provided with a collar 21 of insulating material which affords means whereby the shell may be manipulated. Plate 18, which is shown separately on an increased scale in Fig. 9, overlies the film 22 and holds the film between itself and the inwardly flanged end of the shell 17. In the preferred design, plate 18 is provided with fingers 18^a which enter notches 19^a in the ring 19. These fingers snap over said ring and hold the plate in position. The notches prevent the plate from rotating and damaging the film

when the film holder is being screwed firmly up against the shoe 14.

In operation when the lamp is absent, the spring switch 13^a will engage the inner end of the external shell 2 as shown in Fig. 2 and will thus form a direct path for the current from one of the main binding terminals to the other. When the electrician is ready to install a lamp he provides himself with a film holder containing a film which is intact and screws said holder into the external shell until the plate 18 is in firm electrical contact with the flange 14^a of shoe 14. This puts plate 18 into electrical contact with terminal post 12 but the film 22 insulates said ring from shell 17 of the film holder. The electrician then screws the lamp into the internal shell, the end of the lamp base engaging the post 16 and forcing switch 13^a back out of contact with the external shell. As soon as the switch 13^a has left the external shell (see Fig. 1), the path through said switch will be broken and the current will pass from said switch through post 16 to the center terminal 22^a at the end of the lamp base, thence through the lamp filament 23 to the lamp shell or collar, thence through the internal shell 17 and external shell 2 to the terminal post 5. If now the lamp filament becomes broken, the impressed voltage will cause the penetration or destruction of the film 22 and permit the current to pass directly from the shoe 14 and plate 18 to the inner end of the internal shell 17, thence through the external shell 2 to the terminal.

It will be noted that with my construction the film is carried by a holder which is removable as a whole. In consequence after a film has been burned out it is unnecessary for the electrician to immediately place a new one in the holder. By supplying himself with a number of holders provided with intact films, all he has to do is to replace the holder having a burned out film with a holder having a fresh film. This enables him to replace the burned out film at his leisure and avoids the necessity of working in the dark or under adverse weather conditions or when time for making the rounds is limited. Furthermore with my construction the film holder has no effect upon the switch 13^a and therefore may be inserted or withdrawn without disturbing it. Again, the electrician may screw the lamp into the film holder either before or after the film holder is inserted into the external shell. The sequence in this respect is immaterial and hence it is impossible to misoperate the device in this regard.

Having thus described my invention, what I claim as new and desire to secure by Letters Patent, is:

1. A lamp socket comprising an insulating base provided with two main terminals, a

metallic shell mounted on said base and electrically connected to one of said terminals, a film holder comprising a metallic shell screwing into the first mentioned shell and being internally threaded to receive the lamp, said internal shell having a flange formed at its inner end, an annular metallic plate forming part of said film holder and lying adjacent to the flange of the internal shell, a film normally insulating said plate from the flange of the internal shell, means composed of insulating material for securing said plate to said internal shell, means for electrically connecting said plate to the opposite main terminal when the film holder is in position in the external shell, and means for electrically connecting the center contact of the lamp with the last mentioned terminal.

2. A lamp socket comprising an insulating base provided with two main terminals, a metallic shell inclosed within said base and permanently secured to one of said terminals, a dielectric film, a film holder comprising an annular metallic plate, a metallic shell screwing into the first mentioned shell and having an internal screw thread for receiving the lamp, said internal shell having an annular flange at the inner end substantially co-extensive with said plate and separated therefrom by said film, said film holder also including a ring of insulating material for holding the internal shell and film and annular plate assembled, means for electrically connecting said plate to the opposite main terminal of the device, and means for electrically connecting the center contact of the lamp to the last mentioned terminal.

3. A lamp socket comprising an insulating base provided with two main terminals, a metallic shell inclosed within said base and permanently secured to one of said terminals, a dielectric film, a film holder comprising an annular metallic plate, a metallic shell screwing into the first mentioned shell and having an internal screw thread for receiving the lamp, said internal shell having an annular flange at the inner end substantially co-extensive with said plate and separated therefrom by said film, said film holder also including a ring of insulating material for holding the internal shell and film and annular plate assembled, means for electrically connecting said plate to the opposite main terminal of the device, and a switch electrically connected to the last mentioned terminal, said switch being engaged by the center contact of the lamp and tending to

move into contact with the first mentioned shell.

4. A film socket comprising, in combination with an annular film, an insulating base, two main terminals on said base, a metallic shell inclosed within said base and electrically connected to one of said terminals, a film holder screwing into the first mentioned shell and having an internal screw thread for receiving the base of the lamp, said film holder comprising a metallic shell having formed thereon an annular flange approximately co-extensive with said film, an insulating collar whereby said shell may be manipulated, an annular plate substantially co-extensive with said film and separated by said film from the annular flange on the internal shell, an insulating ring fitting over the inner edge of flange on said internal shell, said plate having spring fingers adapted to snap over said insulating ring for holding the plate in position, and means for electrically connecting said plate to the opposite terminal when the film holder is in position within the first mentioned shell.

5. In a film socket, the combination of an insulating base, two main terminals on said base, a metallic shell located within said base and electrically connected to one of said terminals, an internal metallic shell screwing into the first mentioned shell and having internal screw threads for receiving the base of the lamp, said internal shell having an annular flange at its inner end, an annular film supported upon the flange on the internal shell, an annular plate overlying said film, means for removably holding said plate upon said film, an annular shoe electrically connected to the opposite terminal on the base and located in position to be engaged by said plate when the parts are assembled, a post contact electrically connected to the same terminal as the shoe and adapted to pass through the central opening of the shoe, film, film holding plate and internal shell to energize the center contact of the lamp, and a spring switch electrically connected to and operated by said post and tending to engage the external shell for the purpose described.

In witness whereof, I have hereunto subscribed my name in the presence of two witnesses.
